[57] CLAIM

The ornamental design for a foot massager, as shown and described.

DESCRIPTION

FIG. 1 is a top perspective view of a foot massager showing our new design;

FIG. 2 is a top plan view of the foot massager of FIG. 1;
FIG. 3 is a front elevational view of the foot massager of FIG. 1;

FIG. 4 is a rear elevational view of the foot massager of FIG. 1;

FIG. 5 is a left side elevational view of the foot massager of FIG. 1, the right side elevational view being a mirror image thereof; and,

FIG. 6 is a bottom plan view of the foot massager of FIG. 1.
